ILLUMINATED SIGN AND PUSH BUTTON
UNIT

Charles L. Langlotz, New York, N. Y.

Application April 9, 1936, Serial No. 73,575

12 Claims. (Cl. 40—130)

The purpose of this invention is to provide a novel type of illuminated number sign for houses.

A special feature of novelty of the invention resides in the provision of a combination unit comprising number sign means and an electric push button device associated therewith so that the illuminating means employed, which may be an electric bulb or bulbs, will illuminate both the number indicia of the sign used for the house number, and the push button member as well, enabling the ready location of the push button at night, as well as the identification of the house to which the number sign may be applied.

Another especial object of the invention has been to so design the number sign and push button unit as to enable the same to be quickly and readily applied to the door frame or any equivalent portion of the dwelling upon which the unit is used, without necessitating any substantial or material alteration of the part upon which the unit is to be mounted.

Still another object of the invention resides in the employment of a combination sign and push button unit of the type referred to, which may be readily placed in the low voltage circuit of an electric house bell system, and which will derive its illumination from the current of such system.

Still another and more specific objective in the development of the detail construction of my invention lies in the push button provision per se, the push button being so made as to be transparent or translucent, and adapted to contain directly therein the electric bulb or light by which the sign and push button features of my device are lighted and made readily locatable. However, it is to be understood that my invention includes the provision of a push button member per se, which may be transparent or translucent, being preferably made of glass or the like, the same being illuminated by light means whether the said light means is carried directly by or connected to the push button, or located near the same.

Another feature of my invention lies in the construction of my push button device alone and irrespective of its association with any other device such as a number sign, the push button device comprising features of novelty enabling it to be advantageously employed by itself should such construction be desired.

Still another feature of the invention resides in the construction of the push button device hereof such that it includes a manipulatable member forming a part of the mounting of the push

button itself, by which the control of the passage of current to the light bulb by which the push button is illuminated may be effected. In other words, the said manipulatable member is practically a switch enabling the illumination of the push button to be effected in the evening and turned off in the day-time.

Since the low voltage current of the electric bell system of a dwelling is intended to be used for the illumination of the push button and the number sign device when combined, or when the push button is used alone, provisions are made so that the said current may be availed of and drawn from the electric bell circuit without any ringing of the bell under normal conditions, 15 the manipulation of the push button, however, being such as to act upon the circuit connections and features in such a way as to cause the ringing of the bell whenever desired.

The preferred constructions of my invention are illustrated in several modifications in the accompanying drawing, in which—

Figure 1 is a front elevation of a combination push button and number sign unit embodying the invention.

Figure 2 is a horizontal sectional view through the device of Figure 1.

Figure 3 is an enlarged view showing more fully the push button structure of the device as illustrated in Figures 1 and 2 and bringing out 30 the arrangement of the contacts, the revoluble switch plate, and other adjacent parts.

Figure 4 is a fragmentary detail view of a certain portion of the device of Figures 1 to 3, the view being taken on the line 4—4 of Figure 1.

Figure 5 illustrates a view similar to Figure 2, but being a modified form of the invention.

Figure 6 is a fragmentary plan view of the central portion of the device as illustrated in 40 Figure 5.

Figure 7 is a diagrammatic view of the electric bell circuit adaptable for use with the invention.

Figure 8 is a front elevation of another modification of the invention.

Figure 9 is a front elevation of another modified form of the invention.

Figure 10 is a fragmentary view of a portion of the electric circuit usable for the purposes of the invention.

Referring to the construction of my invention as disclosed in Figures 1 to 4 inclusive, my combination unit comprises the base member 1 of segmental or fan-shaped form, the same provided with an outstanding edge flange 2 and an over-

hanging retaining flange 3. The base member 1 with said flanges forms a hollow structure adapted to receive therein the indicia members 4, which are preferably disposed on an arc 5 forming with the general contour of the base member 1, each member 4 tapering from its outer edge toward its inner edge. Struck up from the base 1 are lugs 5 to engage the lower inner edge of each member 4 to thus hold the outer edge 10 portion of each said member interengaged beneath the flange 3. The base member is equipped on its underside with a casing or housing 6. The said casing or housing 6 has partially mounted therein at its innermost portion the depressible 15 push button 7, see Figure 3, the same passing through an opening in the base 1 and being formed with a shoulder or flange 8 adapted to abut with the base member 1 and be limited in its outward movement thereby. The push button 7 is hollow and preferably made of glass or similar translucent substance. At its inner end portion adjacent to the flange 8, said abutment 20 may be internally threaded as at 9 to enable the threaded portion 10 of an electric light bulb 12 to be screwed therein. I preferably use an electric light bulb of very small candle power such as employed in flashlight lamps commonly on the market. Seated around, and receiving therethrough the push button 7, is a switch or actuating plate 13. This plate is knurled as shown at 13a and capable of being revolved slightly. The member 13 is held in place by a cover plate 14 carried on the base member 1 and overlapping the lower portion of the latter. The cover plate 14 is cut out near its middle portion as shown at 14a, and adjacent to the arc of the cut out portion 30 said plate 14 is formed with a curved flange 14b which fits over the beaded edge portion 13b of the switch plate 13. The switch plate 13 carries an inwardly extending arm 15 adapted to engage 40 with a contact arm 16 secured within the housing 6, said contact arm being of approximately U-form and having its free end adapted for electrical contact with the conductive screw thread portion 10 of the bulb 12. Another spring contact member 17 is secured at 18 in the housing 6 and is adapted to be moved laterally into contact with the secured portion of the contact arm 16 at the point 19.

50 A lead of the electric circuit provided for the lighting of the bulb 12 is connected with the member 16 at the point 19 and is designated 20. Another lead connected with the spring contact 17 and forming a part of said circuit is designated 21 and is connected with the part 17 at the point 18, previously mentioned.

By slight pressure upon and turning of the switch plate 13 the arm 15 thereof may be slightly revolved to move the contact arm 16 away from 60 the conductive member 10 of the bulb 12. This adjustment of the switch plate 13 is utilized to prevent the circuit through the bulb 12 from being completed, so that during the day the bulb may not be lighted and current wasted. Normally, however, when the plate 13 is adjusted to 65 permit contact of the member 16 and the part 10, there will be a sufficient flow of electric current from the lead 21 through the contact 17 to the contact part 10, contacting arm 16, and lead 20, to maintain the so-called flashlight or similar bulb 12 lighted.

The spring contact 17 tends to hold the push button 7 at the outward limit of its movement. There is included in the electric circuit comprising the leads 20 and 21, as will later be pointed

out, an electric bell 22, see Figure 7, and when the push button 7 is pushed inwardly against the normal spring action of the spring contact 17 to connect the lead 21 directly with the lead 20 by the contact member 17 engaging the member 19, the electric bell 22 may be rung.

Since the button 7 is hollow and translucent, and since the bulb 12 is mounted therein, the location of the button will be quite apparent in the night-time through the illumination thereof by this arrangement.

Now referring to Figures 5 and 6, I note that the construction thereof is advantageous because the casing 6 is dispensed with as used in the previously described modification. This enables the 15 base member 23 to be readily placed upon the frame of a doorway without necessitating the formation therein of a recess that is necessary when the casing 6 is used in the construction of Figures 1 to 4. According to the construction of Figures 20 5 and 6, the base member 23 has a cover plate 24 similar to the plate 14. The indicia members 25 are mounted on the base plate 23 as previously described. For supporting the push button, however, there is provided on the outer portion of 25 the base member 23, and held in place by the cover member 24, a housing or casing 26. The housing 26 has a flange 27 adapted to be overhung by a portion of the cover member 24 adjacent the cut out portion 28 of the latter, whereby 30 the housing is held in place on the base member 23 and the part 24. The push button 29 is depressibly mounted in the central opening of the housing 26 and is formed with a shoulder 30 interengaging a semi-circular translucent dome 35 member 31.

The push button 29 is translucent, of course, and the light bulb 32 therein is arranged so that its rays will pass through the member 29 and may be directed upwardly through the transparent dome member 31 so as to light the area of the number sign indicia members 25. This construction, therefore, affords a convenient method of illuminating the sign section of my combination unit with somewhat greater efficiency than 45 afforded by the construction of Figures 1 to 4.

The housing 26 constitutes a switch member because it is rotative in relation to the parts 31 and 24; it has an actuating arm 33 adapted to move the contact member 34 in a manner similar 50 to the action of the parts 15 and 16, and 13, previously described. The push button 29 is outpressed by the contact member 35, and the contact member 34 and the member 35 are connected to leads such as designated 21 and 20 in the construction of the previously described modification. The cover member 24 as shown in Figure 5 is attached to the base member 23 at the points 36 as by screws or the like.

In the construction of my invention according 60 to the modification of Figure 8, I use a combination push button and sign unit in which the sign section is somewhat rectangular in form and designated A. It contains therein the digit or indicia members 37. At its lower portion the 65 sign section of the unit carries a hollow downwardly tapering housing extension B on which the push button 38 is mounted, this push button being of the translucent illuminated type previously described. A push button plate 39 is provided on the section B and the push button contacts are connected with the electric bell circuit as shown in Figure 10. The illumination of the translucent push button 38 and the indicia members 37 is obtained by light bulbs shown in dotted 70 75

lines in Figure 8 and designated 40. A switch 40a on the section B permits turning off of the current for the light bulbs during daytime.

The modification of Figure 9 is in some general respects similar to that of Figure 8, except that the entire combination number sign and push button unit is formed with an illuminated body, with the indicia members 41 arranged vertically, though they could be disposed horizontally, and the push button 42 located near the lower end of the unit. Light bulbs 44 are disposed in rear of and near the ends of the unit as shown in dotted lines and give sufficient light to amply illuminate the digit members 41 and the translucent push button 42. The electric circuit arrangement for the modification of Figure 9 is the same as shown in Figure 10.

Referring to the circuit diagrams of Figures 7 and 10, I describe one form of electric bell circuit suitable for the purposes of the invention, as follows:

This circuit includes the line wires 46 and 47, and connected therein is the usual transformer 48 commonly used in house bell systems today. The lead 20 previously mentioned runs from the circuit wire 47, and the lead 21 from the circuit wire 46. Suitably connected in the side 47 of the circuit is the usual electric bell 22, as mentioned before, and between the leads to said bell unit is interposed the resistance or impedance 48a of a value sufficient to normally prevent ringing of the bell until the push button 7 is depressed sufficiently to connect the spring contact 17 with the contact 19 of the lead 20, thereby momentarily shorting the light circuit including the contact arm 16 and causing the current to flow directly between the leads 20 and 21 with ample voltage for ringing of the bell 22.

The base member has a lug 55 on which the lowermost portion of the rotatable switch member 13 or 26 rests or is supported, this lug extending upwardly from the bottom of the base member and thence forwardly to bear against the rear side of the member 13 or 26, as best seen in Figures 1 and 6.

Having thus described my invention, what I claim as new and desire to secure by Letters Patent of the United States, is—

1. In a push button appliance of the class described, in combination, a base member, a push button movable thereon of translucent substance, a light having its rays directed through the said substance of said button, instrumentalities for supplying electric current to the said light, and a switch member through which the button passes, cooperating with said instrumentalities, and means for movably mounting the switch member on said base member so that the light may be put out or lighted at will.

2. In a push button appliance of the class described, in combination, a base member, a push button movable thereon of translucent substance, a light having its rays directed through the said substance of said button, means connecting the push button and light so that they move as a unit, a movable switch plate surrounding the button and relative to which the button is movable, and contact instrumentalities operable by the switch plate to cause the light to illuminate the button and cut off such illumination.

3. In a push button appliance of the class described, in combination, a base member, a push button movable thereon, a light arranged so its rays may be directed through the button, switch means on said base member cooperating with said

light, and a movable switch plate mounted adjacent to the button and said base cooperating with said switch means for rendering the light operative and inoperative.

4. A combination number sign and bell push button unit comprising a base member, translucent members, indicia on said translucent members, a push button, and a light common to the button and translucent members and disposed substantially in the plane of the latter to thereby illuminate said push button, indicia and translucent members.

5. A combination number sign and bell push button unit comprising a base member, indicia members thereon, a push button, and a light common to the button and indicia members to illuminate them, said light being mounted in the button with its rays directed laterally upon the indicia members, substantially in the plane thereof.

6. A combination number sign and bell push button unit comprising a base member, indicia members thereon, a push button, and a light common to the button and indicia members to illuminate them, said light being mounted in the button with its rays directed upon the indicia members through the body of the button and laterally in approximately the plane of said indicia members, the button being made of translucent substance so the light rays may be directed as stated.

7. A device as set forth in claim 4, wherein the indicia members are disposed radially of the button as a center.

8. A combination number sign and bell push button unit comprising a base member, indicia members thereon, a push button movable on the base, a light for illuminating the indicia members, a switch member through which the button is movable and rotatively mounted on the base, and contact means operable by the switch member to control action of said light.

9. A combination number sign and bell push button unit comprising a base member, indicia members thereon, a push button movable on the base, a light for illuminating the indicia members, a switch member through which the button is movable and rotatively mounted on the base, contact means operable by the switch member to control action of said light, and means for mounting the light on and within the button so as to be visible therethrough.

10. A combination number sign and bell push button unit comprising a base member, indicia members thereon, a push button and light unit carried by the base member, switch instrumentalities cooperating with said button and light unit, said unit including a light bulb disposed on and visible through the push button, a movable switch plate, and an additional switch member on the base member coacting with said switch plate to render the light operative or inoperative.

11. A combination number sign and bell push button unit comprising a base member, indicia members thereon, a push button and light unit carried by the base member, including a light bulb disposed on and visible through the push button, a movable switch member on the base member coacting to render the light operative or inoperative, and a cover plate carried by the base member and interengaging the switch member to hold it in place but permitting its rotation to perform its stated function.

12. A combination number sign and bell push

button unit comprising a base member, indicia members thereon, a push button and light unit carried by the base member, including a light bulb disposed on and visible through the push button, a movable switch member on the base member coacting to render the light operative or inoperative, a cover plate carried by the base member and interengaging the switch member to hold it in place but permitting its rotation

to perform its stated function, the cover plate being disposed at the lower portion of the base member, and the indicia members at the upper portion, with the push button therebetween, and the switch member surrounding the push button which passes therethrough, and a contact actuating arm carried by the switch member.

CHARLES L. LANGLOTZ.
